(No Model.)

L. L. SAGENDORPH.

MACHINE FOR LOCKING SHEET METAL JOINTS.

No. 398,655.

Patented Feb. 26, 1889.

UNITED STATES PATENT OFFICE.

LONGLEY LEWIS SAGENDORPH, OF CINCINNATI, OHIO, ASSIGNOR OF ONE-HALF TO HARLAN P. LLOYD, OF SAME PLACE.

MACHINE FOR LOCKING SHEET-METAL JOINTS.

SPECIFICATION forming part of Letters Patent No. 398,655, dated February 26, 1889.

Application filed September 20, 1888. Serial No. 285,883. (No model.)

To all whom it may concern:

Be it known that I, LONGLEY LEWIS SAGENDORPH, a citizen of the United States, and a resident of Cincinnati, Hamilton county, 5 State of Ohio, have invented certain new and useful Improvements in Machines for Locking Sheet-Metal Roofing-Joints, of which the following is a specification.

In the drawings accompanying this specification and forming a part thereof, Figure 1 is a side elevation of my improved machine. Fig. 2 is a central vertical section taken through the two clamping-bars, showing two sheets of metal in position ready to be clamped and locked. Fig. 3 shows a section of two sheets of metal after having been clamped and locked by my improved machine.

Heretofore sheets of metal roofing have been joined by providing each sheet of metal 20 with overlapping end flanges, adapted to engage each other when placed in position, and then subjecting the ends of the sheets and flanges to a pressure, which formed a lock-joint. The objection to this method of joining sheets of metal is that in handling the sheets or in rolling them for shipment the sheets are liable to become separated, as the compressed flanges are on the same plane for the entire width of the sheet, and much valuable time is lost in replacing the sheets in 25 position relative to each other.

The object of my invention is to provide a machine which will clamp the end flanges of the sheets together for their entire width, 30 and at the same time form a depression, a^3 , in the ends of said sheets and flanges for the greater part of their width, (not the entire width,) in order to securely lock the same and prevent any displacement of the sheets while 35 being handled or rolled. The blank portion of the sheets in which the depression a^3 is not formed is intended to be utilized for forming a standing seam for adjoining side sheets.

40 My invention is constructed as follows: The two clamp-bars A and B are mounted between suitable end frames, C, made fast to the lower stationary bar, B, which latter is rigidly connected to the platform D in any 45 suitable manner. The clamp-bar A is placed

in position over the stationary bar B and adapted to move vertically between the end frames, C. This movable bar A is upheld in position between said end frames by suitable spiral springs, a , (shown by dotted lines in Fig. 1,) which rest in suitable countersunk portions in the said clamp-bars, as shown. These springs may be of any other suitable configuration, or, if desired, rubber may be used, the object being to afford a means for 55 keeping the bar A elevated and away from the stationary bar B, except when operated upon by the eccentric lever, as will more fully hereinafter appear.

The lower stationary clamp-bar, B, has two 60 rib projections, b , on its upper face, forming a flat groove, b' , between them for the entire length of the bar, or at least between the end frames, which groove is about the width of the flange on the lower sheet of metal. A 65 corresponding groove, a' , is also formed in the bottom face of the movable bar A for the flange of the upper sheet to rest in when clamped together.

Near the center of the flat groove b' is 70 formed a longitudinal semicircular groove, b^2 , (shown in Fig. 2 and by dotted lines in Fig. 1,) for the greater length of said bar B, but not the entire length thereof, as shown in Fig. 1. To the bottom face of the movable 75 bar A, and near the center of the groove a' , is fast or suitably secured a longitudinal rib, a^2 , corresponding in configuration with the groove b^2 , and adapted to fit therein when said bar is lowered.

The vertically-movable clamp-bar A is in 80 the present illustration operated by means of the eccentric lever E and auxiliary eccentric E', said eccentrics being connected by an adjustable rod, E².

The operation of my device is as follows: A suitable table (not shown) is provided at 85 each side of the machine at about a level with the top of the stationary bar B, on one side of which the metal to be joined is placed. The sheets are first provided with the overlapping flanges and hooked together, and are 90 then drawn in between the clamp-bars A and B until the top sheet strikes against the guide-pins F, as shown in Fig. 2, which latter 95

rest loosely in holes drilled in the movable bar A. The top bar is now made to descend through the medium of the eccentrics E and E', which causes the overlapping flanges of 5 the sheets to be tightly pressed in the grooves b' and a' and at the same time forms the longitudinal depression a³ in said sheets and flanges, corresponding to the groove b² and rib a² of the clamp-bars. After forming this 10 depression the eccentric lever is raised, when the bar A is elevated to place again by means of the springs a.

Instead of employing but one continuous rib and groove, a series of ribs and grooves 15 may be formed in said clamp-bars; but it is preferred to use but one rib and groove, as shown.

Any suitable operative mechanism may be

employed for raising and lowering the clamp-bar A.

What I claim as new, and desire to secure 20 by Letters Patent, is—

In a machine for locking the joints of sheet metal, the lower stationary bar, B, having the ribs b and flat groove b' between them, and 25 a semicircular groove, b², near the center of said groove b', in combination with the movable bar A, having the flat groove a' in its under face and a rib projection, a², near the center of said groove a', and suitable mechanism 30 for operating said movable bar.

LONGLEY LEWIS SAGENDORPH.
